SPRING COILER

Edward H. Hoelsch, Worcester, Mass., assignor to
Perkins Machine & Gear Company, West
Springfield, Mass., a corporation of Massachusetts

Application May 14, 1951, Serial No. 226,212

7 Claims. (Cl. 153—65)

1

This invention relates to a spring coiler and more particularly to a coiler for making springs of various types, diameters and pitch. In laboratories and shops it often happens that a few or perhaps only one of a particular spring is required for a special purpose. The spring may be a standard or special type, but in either event there is some time required to obtain the spring. The cost of special types of spring is considerable. It has been suggested to use small hand operated spring coilers for the purpose of making such springs. However, such coilers that are now available are expensive and difficult to set up for different springs. In many instances it is necessary to change arbors and other parts to make springs of different sizes and types.

It is therefore an object of my invention to provide a hand spring coiler that is inexpensive, easily set up for different sizes and types of spring, and in which the parts thereof need not be changed for different springs.

These and other objects will be more apparent after referring to the following specification and attached drawings, in which:

Figure 1 is a top plan view of the machine;

Figure 2 is a front elevation of the machine;

Figure 3 is an enlarged side elevation looking from the left of Figure 1;

Figure 4 is an enlarged fragmentary view of a detail;

Figure 5 is an enlarged fragmentary front elevation;

Figure 6 is a sectional view taken on the line VI—VI of Figure 5; and

Figure 7 is a view of a detail.

Referring more particularly to the drawings, the reference numeral 2 represents the body or frame of the coiler. A pair of spaced apart rearwardly extending lugs 4 and 6 are arranged on the body 2. Aligned openings 8 and 10 are provided in the lugs 4 and 6, respectively, and are provided with bearings for receiving a rotatable shaft 12. One end of the shaft 12 extends outwardly from the lug 4 and has a handwheel 14 fastened to its outer end. The other end of the shaft 12 extends through the lug 6 and has a worm 16 fastened thereon. A lug 18 extends upwardly on the body 2 at the left hand end thereof as seen in Figure 1. An axial opening 20 extends through the lug 18 at right angles to the shaft 12 and is provided with bearings for receiving a rotatable shaft 22. A worm wheel 24 which meshes with worm 16 is mounted on the back end of shaft 22 and is held in place by means of set screw 25. A gear 26 is mounted on the shaft 22 between the lug 18 and worm wheel 24 and is held in place by means of a set screw 21. A feed roll 28 is mounted on the front end of shaft 22 for rotation therewith. A pair of spaced apart lugs 30 and 32 extend from the left side of the body 20

as best shown in Figure 3. Aligned openings 34 are provided in the lugs 30 and 32 for receiving a pin 36 on which is mounted a feed roll pressure arm 38 which is received between the lugs 30 and 32. The arm 38 has a bearing 40 on its upper end. The axis of bearing 40 is parallel to the axes of shaft 22 and pin 36. A shaft 42 is received in the bearing 40 and extends from both ends thereof. A gear 44 is meshed with gear 26 and is fastened to the rear end of shaft 42 by means of a set screw 45. A feed roll 46 having a circumferential groove 48 therein is fastened to the front end of shaft 42. As best shown in Figure 2, a threaded opening 50 is provided in the body 2 for receiving a stud 52 which passes through an opening 54 in arm 38. A knob 56 is fastened to the stud 52 with a spring 58 being located between the arm 38 and knob 56. A set screw 60 is threaded into the lug 32 and bears against the pin 36 to hold it in adjusted position.

As best shown in Figure 5, a two-part guide is fastened to the body 2 immediately below the feed rolls 28 and 46 by means of countersunk screws 61. The left hand guide member 62 has a groove 64 on its inner vertical edge which abuts the right hand guide member 66. Two holes 68 and 70 are provided in the body 2 directly below the guide members 62 and 66 for receiving the shafts of pitch tools 72 and 74. The shafts extend rearwardly from the body 2 as seen in Figure 4. A counterbored hole 76 is provided in the body 2 between and slightly below the holes 68 and 70. An arbor sleeve 78 is received in the counterbored portion of hole 76 and has a forwardly extending guide portion 80 extending beyond the body 2. Radial grooves 82 are provided on the guide 80 as best shown in Figure 7. The sleeve 78 has an axial opening 84 therein having a diameter equal to that of the hole 76. An arbor 86 is received in the hole 76 and opening 84 with its front end against the back of guide portion 80. An eccentric pin 88 extends from the front end of arbor 86. The other end of arbor 86 extends rearwardly from the body 2 and has an eccentric pin 90 extending therefrom as shown in Figure 3. The sleeve 78 may be rotated about its axis and is held in adjusted position by means of a brass shoe 92 and an adjusting screw 94 which are received in a threaded hole 96 in body 2 (see Figures 1 and 2). The arbor 86 may be rotated about its axis and is held in adjusted position by means of a brass shoe 98 and an adjusting screw 100 which are received in a threaded hole 102 in the body 2.

As best shown in Figures 3 and 4, a yoke 104 is fastened to the rear end of the shafts of pitch tools 72 and 74 by means of set screws 106. A spring 107 surrounds the rear end of arbor 86 which is slidably received in a hole 108 in yoke 104 and passes therethrough with a collar 110.

being fastened to the end thereof. The spring 107 bears against the body 2 and yoke 104. A lever 112 is pivotally mounted on the body 2 by means of a bolt 114 screwed into an opening 116 in lug 6. One end of lever 112 bears on yoke 104 and the other end has a pin 118 in engagement therewith. The pin 118 is slidably mounted in an opening 120 in body 2 and its position is adjusted by means of an adjusting screw 122 threaded into an opening 124 in body 2. The spring 107 keeps the yoke 104 in engagement with the lever 112 at all times.

As best shown in Figure 5, a coiling point 126 is received in an opening 128 of a holder 130 and held in place therein by means of a brass shoe 132 and a set screw 134 which are received in a threaded opening 136. The coiling point 126 has a groove 137 at each end thereof. The holder 130 has a shaft 138 which is held in place in an opening 140 in an arm 142 of a two-armed lever 144 by means of a set screw 146. As seen in Figure 2, the lever 144 has an opening 148 therein for receiving an eccentric bushing 150 which has a counterbored opening 152 therein for receiving a cap screw 154 which is screwed into a threaded opening in the body 2. The other arm 156 of the lever 144 extends downwardly and has a threaded opening 158 therein for receiving an adjustable stop screw 160. A threaded collar 162 is threaded on the screw 160. The end of the stop screw 160 abuts against a stop 164 which is mounted on a pin 166 for rotation therewith. The pin 166 extends through openings in spaced apart lugs 168 on the body 2 and through an opening in the stop 164 which is received in the space between the lugs. A set screw 170 holds the pin 166 in adjusted position.

An end former 172 is received in an opening 174 in the right hand end of body 2 and is held in place therein by means of a cap screw 176.

The operation of the device is as follows:

With the various parts positioned as shown in Figures 5 and 6, a rod or wire W is inserted between the feed rolls 28 and 46 and the handwheel 14 is turned in a clockwise direction as shown in Figure 3 to feed the wire down through the groove 64 in the guide member 62. In case the wire slips, the stud 52 is turned by means of the knob 56 to increase the pressure between the feed rolls 28 and 46. The set screw 170 is loosened and the stop 164 permitted to drop to its lower position, thus permitting the coiling point 126 to drop away from coiling position. The adjusting screws 94 and 100 are loosened and the sleeve 78 and arbor 86 rotated about their axes to bring the guide 80 and pin 88 in the position shown in Figure 5, after which the screws 94 and 100 are tightened. The end of the wire is then bent around the pin 88 and the coiling point 126 is brought up into contact with the wire W. The stop 164 is then raised into the position shown in Figure 2 and fastened there by tightening set screw 170. Right hand pitch tool 72 is then positioned as shown in Figures 5 and 6 and held in this position by set screw 106. Rotation of handwheel 14 is then continued, thus causing the wire W to coil continuously about pin 88. When the spring is completed the coiling point 126 is dropped in the manner described above. Continued rotation of handwheel 14 feeds the spring and wire W downwardly without further coiling after which the spring is cut off and the end thereof formed in the desired manner on the end former 172. The machine is then ready for another operation.

When it is desired to increase the diameter of the spring, the screw 160 is threaded outwardly, thus permitting the lever 144 to rotate in a counterclockwise direction. To decrease the diameter the screw is threaded inwardly. This operation may be performed during feeding of the wire W to make a spring of varying diameter.

The pitch of the same or different springs may be varied by turning screw 122, thus moving the pitch tool 72 inwardly or outwardly.

To make a left hand spring the pitch tool 72 is moved to a vertical position and the left hand pitch tool 74 is positioned as shown in broken lines in Figure 5. The positions of guide 80 and pin 88 are also reversed with the guide 80 being to the right and the pin 88 to the left of the guide groove 64.

While one embodiment of my invention has been shown and described, it will be apparent that other adaptations and modifications may be made without departing from the scope of the following claims.

I claim:

1. A coiler for making a spring from a wire comprising a frame, a coiling point mounted on said frame, said coiling point having a groove therein, means for feeding said wire into said groove, said frame having a hole therein adjacent the coiling point, an arbor sleeve in said hole, a guide portion on said arbor sleeve having an edge thereof in substantial alignment with the groove in said coiling point, said sleeve having an axial hole therein, an arbor mounted in said axial hole, a pin mounted eccentrically on the outer end of said arbor and spaced from the edge of said guide portion a distance slightly greater than the diameter of said wire, and a pitch tool mounted on said frame with a portion thereof adjacent said arbor pin.

2. A coiler for making a spring from a wire comprising a frame, a coiling point mounted on said frame, said coiling point having a groove therein, means for feeding said wire into said groove, said frame having a hole therein adjacent the coiling point, an arbor sleeve in said hole, a guide portion on said arbor sleeve having an edge thereof in substantial alignment with the groove in said coiling point, said sleeve having an axial hole therein, an arbor mounted in said axial hole, a pin mounted eccentrically on the outer end of said arbor and spaced from the edge of said guide portion a distance slightly greater than the diameter of said wire, a pitch tool slidably mounted in said frame with its axis substantially parallel to the axis of said sleeve, means on said pitch tool extending toward said pin and terminating adjacent thereto, means for adjusting the axial position of said pitch tool, and means for holding the pitch tool in adjusted position.

3. A coiler for making a spring from a wire comprising a frame, a coiling point mounted on said frame, said coiling point having a groove therein, a pair of feed rolls for feeding said wire toward said coiling point, means for rotating said feed rolls, a guide extending substantially at right angles to the axes of said rolls, said guide having a groove therein aligned with the groove in the coiling point, means for mounting said coiling point for movement toward and away from said guide, said frame having a hole therein adjacent the coiling point, an arbor sleeve in said hole, a guide portion on said arbor sleeve having an edge thereof in substantial alignment with the groove in said coiling point, said sleeve having an axial

hole therein, an arbor mounted in said axial hole, a pin mounted eccentrically on the outer end of said arbor and spaced from the edge of said guide portion a distance slightly greater than the diameter of said wire, and a pitch tool mounted on said frame with a portion thereof adjacent said arbor pin.

4. A coiler for making a spring from a wire comprising a frame, a coiling point mounted on said frame, said coiling point having a groove therein, a pair of feed rolls for feeding said wire toward said coiling point, means for rotating said feed rolls, a guide extending substantially at right angles to the axes of said rolls, said guide having a groove therein aligned with the groove in the coiling point, means for mounting said coiling point for movement toward and away from said guide, said frame having a hole therein adjacent the coiling point, an arbor sleeve in said hole, a guide portion on said arbor sleeve having an edge thereof in substantial alignment with the groove in said coiling point, said sleeve having an axial hole therein, an arbor mounted in said axial hole, a pin mounted eccentrically on the outer end of said arbor and spaced from the edge of said guide portion a distance slightly greater than the diameter of said wire, a pitch tool slidably mounted in said frame with its axis substantially parallel to the axis of said sleeve, means on said pitch tool extending toward said pin and terminating adjacent thereto, means for adjusting the axial position of said pitch tool, and means for holding the pitch tool in adjusted position.

5. A coiler for making a spring from wire comprising a frame, a feed roll rotatably mounted on said frame, a pressure arm pivotally mounted on said frame for movement to and from said feed roll, a second feed roll mounted on said pressure arm adjacent said first feed roll, resilient means for holding said second feed roll in adjusted position adjacent the first feed roll, at least one of said rolls having a groove therein for receiving said wire, means for rotating said feed rolls, a guide extending substantially at right angles to the axes of said rolls, said guide having a groove therein aligned with the groove in the feed roll, a coiling point mounted on said frame and having a groove therein in substantially the same plane as the groove in said guide but substantially at right angles thereto, means for mounting said coiling point for movement toward and away from said guide, said frame having a hole therein adjacent the coiling point, an arbor sleeve in said hole, a guide portion on said arbor sleeve having an edge thereof in substantial alignment with the groove in said coiling point, said sleeve having an axial hole therein, an arbor mounted in said axial hole, a pin mounted eccentrically on the outer end of said arbor and spaced from the edge of said guide portion a distance slightly greater than the diameter of said wire, and a pitch tool mounted on said frame with a portion thereof adjacent said arbor pin.

6. A coiler for making a spring from a wire comprising a frame, a feed roll rotatably mounted on said frame, a pressure arm pivotally mounted on said frame for movement to and from said feed roll, a second feed roll mounted on said pressure arm adjacent said first feed roll, resilient means for holding said second feed roll in adjusted position adjacent the first feed roll, at least one of said rolls having a groove therein for receiving said wire, means for rotating said

feed rolls, a guide extending substantially at right angles to the axes of said rolls, said guide having a groove therein aligned with the groove in the feed roll, a coiling point mounted on said frame and having a groove therein in substantially the same plane as the groove in said guide but substantially at right angles thereto, means for mounting said coiling point for movement toward and away from said guide, said frame having a hole therein adjacent the coiling point, an arbor sleeve in said hole, a guide portion on said arbor sleeve having an edge thereof in substantial alignment with the groove in said coiling point, said sleeve having an axial hole therein, an arbor mounted in said axial hole, a pin mounted eccentrically on the outer end of said arbor and spaced from the edge of said guide portion a distance slightly greater than the diameter of said wire, a pitch tool slidably mounted in said frame with its axis substantially parallel to the axis of said sleeve, means on said pitch tool extending toward said pin and terminating adjacent thereto, means for adjusting the axial position of said pitch tool and means for holding the pitch tool in adjusted position.

7. A coiler for making a spring from a wire comprising a frame, a feed roll rotatably mounted on said frame, a pressure arm pivotally mounted on said frame for movement to and from said feed roll, a second feed roll mounted on said pressure arm adjacent said first feed roll, resilient means for holding said second feed roll in adjusted position adjacent the first feed roll, at least one of said rolls having a groove therein for receiving said wire, means for rotating said feed rolls, a guide extending substantially at right angles to the axes of said rolls, said guide having a groove therein aligned with the groove in the feed roll, a coiling point mounted on said frame and having a groove therein in substantially the same plane as the groove in said guide but substantially at right angles thereto, means for mounting said coiling point for movement toward and away from said guide, said frame having a counterbored hole therein substantially parallel to the axes of the rolls, the counterbored portion of the hole being adjacent the coiling point, an arbor sleeve in said counterbored portion, a guide portion on said arbor sleeve having an edge thereof in substantial alignment with the groove in said guide, said sleeve having an axial hole therein, an arbor mounted in said axial hole, a pin mounted eccentrically on the outer end of said arbor and spaced from the guide portion of said arbor sleeve a distance greater than the diameter of the wire, a pitch tool slidably mounted in said frame with its axis substantially parallel to the axis of said sleeve, means on said pitch tool extending toward said pin and terminating adjacent thereto, means for adjusting the axial position of said pitch tool, and means for holding the pitch tool in adjusted position.

EDWARD H. HOELSCH.
